UNITED STATES PATENT OFFICE.

JOHN W. ROUGH, OF NEW ROCHELLE, NEW YORK.

BOAT.

SPECIFICATION forming part of Letters Patent No. 317,020, dated May 5, 1885.

Application filed March 11, 1885. (No model.)

To all whom it may concern:

Be it known that I, JOHN W. ROUGH, a citizen of the United States, and a resident of New Rochelle, in the county of Westchester and 5 State of New York, have invented certain new and useful Improvements in Boats, of which the following is a specification.

The invention relates to improvements in boats; and it consists in a novel construction 10 embracing a center-board and shoe with connecting devices adapted to be readily attached to or removed from the boat at will, and which, when applied to the boat, will fit it for sailing purposes.

15 The invention will be fully understood from the detailed description hereinafter presented, reference being had to the accompanying drawings, in which—

Figure 1 is a side elevation of a canoe, showing the application of the invention. Fig. 2 20 is a top view of same, the center-board, shoe, rudder, and operating cords or ropes being indicated by dotted lines. Fig. 3 is a vertical transverse section on the line $x-x$ of Fig. 1; 25 and Fig. 4 is a bottom view of the shoe, center-board, attaching-straps, rudder, and operating-cords.

In the drawings, A designates the canoe, of 30 usual construction, having upon its bottom a center-board B, which is formed of thin material of gradually-increasing depth toward its rear end, and is secured at its upper edge in the longitudinal groove C, cut in the lower surface of the shoe D. The center-board B is 35 strengthened by vertical cleats E, secured upon its opposite sides adjacent to its ends, and which cleats taper gradually from the shoe downward toward the lower edge of the center-board. The shoe D is elongated in form, and 40 is adapted to snugly fit the bottom of the boat at about its center. Its particular length and width will depend upon the size and character of the boat, the essential requisite being that in all instances it shall be of sufficient dimensions to receive the center-board and firmly sustain it against the bottom of the boat.

The position of the shoe D on the boat is clearly indicated by dotted lines in Fig. 2.

The shoe D is secured by means of straps F, 50 one being at each end thereof and passing between its under surface and the upper edge of

the center-board, as shown in Fig. 4. The straps F will preferably be formed of thin spring-brass, and will be rigidly secured to the shoe D. The straps F at one end are provided with apertures G, which may be caught upon the hooks H, secured to one side of the boat near its upper edge, while the other end of the straps F are provided with leather extensions I, adapted to be retained by buckles J, attached to the side of the boat opposite to the hooks H, substantially as indicated in Figs. 2 and 3. The length of the straps F on each side of the center-board will vary, of course, according to the size of the boat. They 55 will, however, in every case be of proper length to admit of the shoe and center-board being located upon the center of the bottom of the boat.

Upon the vertical rear edge of the center-board B is pivotally secured a rudder, N, of suitable form and dimensions, and to opposite sides of the rear portion of which are secured the cords O, which pass upward and forward to and through the eyes or blocks P, thence 75 rearward through the similar eyes or blocks, Q, in convenient position to be grasped by the hand of the person sitting in the stern of the boat.

The rudder will be operated in the customary 80 manner, and will be located in rear of the vertical transverse center of the boat.

In applying the shoe, center-board, and rudder it will be found convenient to attach the rudder, and then from the inside of the boat 85 slip the shoe directly under the bow of same, thence moving it to its proper position and securing the ends of the straps F. If the straps are connected by cords extending over the boat while the shoe is being passed under the 90 same, their ends may be readily grasped and secured upon the hooks H and buckles J without difficulty, and there will be no danger of the shoe floating away. It will be plain, of course, that to remove the shoe and center-board it will only be necessary to first loosen the buckled end of the straps F, and then detach their other end from the hooks H.

It should be observed that the shoe may be applied and removed at will without cutting 100 the boat or permanently affixing thereto any device tending to mar its appearance or im-

pede its progress through the water. Upon the shoe and center-board being attached the boat may be used for sailing purposes, and upon the removal of the shoe and center-board 5 therefrom it is restored to its original condition, and may be employed as before without detriment.

I do not limit the invention to its application to canoes, or to any particular floating 10 craft by whatever name known, nor to any particular materials for constructing the parts of same; but

What I claim as new, and desire to secure by Letters Patent, is—

15 1. The shoe adapted to fit the under surface of the boat and carrying a center-board, combined with straps by which the shoe may be attached to the boat or detached therefrom at will, substantially as set forth.

20 2. The shoe adapted to fit the undersurface of the boat and carrying a center-board, combined with a rudder attached to the heel of the center-board, cords for operating the rudder, and straps by which the shoe may be ap-

plied to or removed from the boat at will, substantially as set forth.

3. The shoe D, carrying the center-board B, combined with the straps F, and the hooks H, and buckles J, secured to the boat, substantially as set forth.

4. The shoe D, carrying the center-board B, in combination with the rudder secured at the heel of the center-board, the cords O, and eyes or blocks P Q, substantially as set forth.

5. An attachment for a boat, consisting of 35 the elongated shoe D, fitting the under surface of the boat, the center-board B, rigidly affixed to the under side of the shoe, and projecting at right angles therefrom, and the straps F, by which the shoe is held in place on the boat, 40 substantially as set forth.

Signed at New York, in the county of New York and State of New York, this 9th day of March, A. D. 1885.

JOHN W. ROUGH.
